CLAIM

The ornamental design for LED driving light for a motorcycle, as shown and described.

DESCRIPTION

FIG. 1 is a top view of the light design;

FIG. 2 is a bottom view thereof;

FIG. 3 is a front view thereof;

FIG. 4 is a left-side view thereof;

FIG. 5 is a right-side view thereof;

FIG. 6 is a top-side vertical view thereof;

FIG. 7 is a bottom-side vertical view thereof; and,

FIG. 8 is a back view thereof.

My light design is a LED light suitable for various types of motorcycles, which can be also installed to pillar A and bumpers of SUVs, All Terrain Vehicles and electric bicycles. FIG. 4 shows the fan cowl of the light, inside of which is a fan. FIG. 5 shows the optical lens of the design. The circle in FIG. 6 and the three circles in FIG. 7 are screw holes for fixing brackets.
